UNITED STATES PATENT OFFICE.

CHARLES H. GRAEF, OF EDGEWATER, NEW YORK.

DESIGN FOR A COMB.

SPECIFICATION forming part of Design No. 13,179, dated August 15, 1882.

Application filed June 3, 1882. Term of patent 7 years.

To all whom it may concern:

Be it known that I, CHARLES H. GRAEF, of the village of Edgewater, in the county of Richmond and State of New York, have invented 5 a new and original Design for the Ornamentation of a Comb, of which the following is a specification.

This design consists in the combination, with a comb such as is worn in the hair, of various 10 devices formed in high relief and arranged upon the plain portion, to impart an ornamental appearance thereto.

In the accompanying drawings, Figure 1 is 15 a top view of a comb embodying my design, and Fig. 2 is an edge view thereof.

Similar letters of reference designate corresponding parts in both figures.

The comb has two side portions, A, which are provided with teeth to hold in the hair, 20 and an intermediate band-like portion or band, B. On this band are arranged a representation of a flower, C, and a number of leaves, D. As shown but one flower is used; but I may use any desirable number of flowers. This 25 flower is arranged at the center of the band, and is striated with the exception of the representation of the petals a, which are preferably polished bright, and may consist of small glass beads or of a large glass bead having several 30 protuberances. The leaves are arranged so as to extend toward the toothed side portions of

the comb. As shown they are chased or engraved, and have near the stem portion bright polished knobs, b, which may consist of glass beads. The flower and leaves are in high relief. They may be made separate from the band of the comb and affixed thereto by rivets or otherwise.

It will be observed that by my design I impart to a comb a very beautiful appearance. 40 I consider the band portion B alone as of my invention, and without the toothed side portions, A, it may be used as an ornament for the hair.

What I claim as my design, and desire to 45 secure by Letters Patent, is—

1. The design for the ornamentation of a hair band or comb, substantially as herein specified.

2. The design for the ornamentation of a 50 hair band or comb, consisting of the flower in high relief, with the highly-polished bright representations of petals, substantially as specified.

3. The design for the ornamentation of a 55 hair band or comb, consisting of the leaves D and bright-polished knobs b, substantially as specified.

CHAS. H. GRAEF.
